UNITED STATES PATENT OFFICE.

JOHN W. SMITH, OF ERIE, PENNSYLVANIA.

STEAM-TURBINE.

No. 806,298.

Specification of Letters Patent.

Patented Dec. 5, 1905.

Application filed January 27, 1905. Serial No. 242,904.

To all whom it may concern:

Be it known that I, JOHN W. SMITH, a citizen of the United States, residing at Erie, in the county of Erie and State of Pennsylvania, 5 have invented certain new and useful Improvements in Steam-Turbines, of which the following is a specification.

This invention relates generically to steam-turbines of that class in which the steam is 10 caused to pass successively through separate series of buckets and in which the steam or other motor fluid is guided from one series of buckets to the next following series, partaking in its course of a spiral path from the 15 steam-inlet to the steam-outlet.

The invention relates more particularly to improvements to United States Patent No. 777,313, issued to me December 13, 1904, and to an application for a patent filed January 20 12, 1905, under Serial No. 240,750, to which reference is here made. These inventions relate to a system of guiding the steam from the steam-inlet to the steam-outlet of the casing in a spiral path with that part of the 25 path which the steam-path takes from the outlet ends of one series of buckets to the inlet ends of the next series of buckets of gradually-increasing size.

This invention relates to an improvement 30 over this system in that the steam is guided also in a spiral path from the steam-inlet to the steam-outlet of the casing, but that each part of the path connecting the outlet ends of one series of buckets with the inlet ends of 35 the next series of buckets is of the same cross-section throughout its length, each successive path, however, being of greater cross-section and of greater size than the preceding one.

For this purpose the invention consists of 40 a steam-turbine comprising a casing having steam-inlets and steam-outlets, a turbine-wheel, a plurality of buckets thereon, and means adapted to receive the steam emanating from the outlet ends of the buckets and to 45 guide the same into the inlet ends of the next series of buckets, causing the steam to partake of a spiral path from the steam-inlet to the steam-outlet of the casing, said means being so arranged that the part connecting the 50 outlet ends of one series of buckets with the inlet ends of the next series of buckets is of larger size than the preceding part, each part being of equal cross-section throughout its

length; and the invention consists, further, in certain novel features and combinations of 55 parts which will be fully described herein-after and finally pointed out in the claims.

In the accompanying drawings, Figure 1 represents a development of a portion of my improved steam-turbine, showing the buckets, the guide channels or chambers, admission-blades for directing the steam into the inlet ends of the buckets and curved release-blades adapted to direct the steam emanating from the outlet ends of the buckets into and 60 through the guide channels or chambers, each of said guide channels or chambers being of larger size and greater cross-section than the preceding one, but each having the same cross-section throughout its length. Fig. 2 is a 65 vertical transverse section of the casing and the turbine-wheel, taken on line 2 2, of Fig. 1, showing the division-wall of the buckets secured to the turbine-wheel. Fig. 3 shows a development of a portion of a modified form 70 of my improved turbine having two inlet-nozzles and showing the buckets, the guide-channels and admission-blades in the guide-channels for directing the steam to the inlet ends of the buckets and showing clearly the 75 guide-channels each of a greater size than the preceding one. Fig. 4 shows a development of a portion of a modified form of my improved turbine having a single inlet-nozzle and no admission-blades, and Fig. 5 is a vertical transverse section of Fig. 3, taken on line 80 5 5 and showing clearly the guide-channels, one being of larger size than the other.

Similar letters of reference indicate corresponding parts.

Referring to the drawings, and more particularly to Fig. 1, C represents a casing provided with a steam-inlet E. A represents a turbine-wheel of an axial-flow turbine embodying my invention which is provided at its periphery with a plurality of curved buckets B. These buckets B are formed by mortising curved channels in the turbine-wheel. They may be of the same cross-sectional area throughout their lengths. They may be circular or rectangular in cross-section, or the mortised channels may have their inlet and outlet ends of rectangular cross-section and their central part rectangular in cross-section with rounded corners or approximately circular. These channels may be lined with closed 85 90 95 100 105

tubes of proper shape or may be left simply as such, as shown in the drawings, and division-walls provided adapted to form, with the channels, buckets. In case detachable tubular 5 buckets are used, or in such other cases where it is deemed advisable, the casing C is at its lower end on a plane with the inlet and outlet ends of the buckets, as shown in Fig. 2, and the turbine-wheel is provided with a ring R, 10 secured thereto, so that the space between the wheel A and the ring R forms the buckets proper.

In a preferable form of bucket construction (shown in Figs. 3 and 5) the casing C is provided at its lower end with a downwardly-extending curved portion R' and the turbine-wheel provided not alone with the series curved channels, but with a circular channel concentric with its periphery, by means of which the 15 turbine-wheel may be rotated without being obstructed by the extension, while the space between the extension and the turbine forms the buckets proper. The buckets are so arranged that the steam is discharged parallel 20 to, but in a direction opposite to the entering steam.

The casing C (shown in Fig. 1) is provided with partitions D, D', and D'', parallel to each other, which divide the casing into chambers, 25 each chamber having at each point the same cross-sectional area, one chamber being larger or of greater cross-section than the preceding one. Steam enters the casing C by the steam-inlet E and is directed by the admission-blades 30 F into the steam-inlet ends of a series of buckets B. The steam impinging against the buckets expends part of its energy in impulse and reaction and so in propelling the turbine-wheel onwardly converts that part of its energy 35 into useful work. The steam emanating from the outlet ends of the buckets enters again the casing immediately above the outlet ends of the buckets, being received by a chamber formed by the casing and partitions D and D' and so formed as to be of the 40 same cross-section at every point throughout its length. This channel or chamber directs the steam back toward the inlet ends of the next series of buckets B and then, by means 45 of the admission-blades F, into the inlet ends of the buckets, where the energy resident in the same is again converted to useful work in propelling the wheel onwardly. This steam passing through the buckets and emanating 50 from the outlet ends of the same enters the inlet end of the next chamber formed by the casing and partition-walls D' and D'' and is directed by this chamber to the inlet ends of the next series of buckets, from the outlet ends 55 of which it emanates and passes into a suitable condenser or exhausts into the atmosphere. The chamber formed by the walls of the casing C and partitions D' and D'' is also

at every point of its length from its inlet directly above the outlet ends of the buckets 60 to its outlet end directly above the inlet ends of the buckets of the same cross-sectional area; but the chamber formed by the walls of the casing and partitions D' and D'' is greater in cross-sectional area than the chamber 70 formed by the walls of the casing and the partitions D and D'.

Those parts of the partitions extending downwardly in proximity to the inlet ends of the buckets, as well as the admission-blades, 75 are tapering in shape, so as to insure an efficient entrance velocity of the steam entering the buckets. Those parts of the partitions extending downwardly into proximity to the outlet ends of the buckets are scoop-shaped 80 at their lower ends, and intermediately between the partitions are arranged scoop-shaped or curved release-blades G for the purpose of giving the steam a forward turn and so directing the steam forwardly toward the 85 outlet end of the chamber.

In Fig. 3 is shown a modified but preferable form of my improved turbine, which is especially adapted for the use of gas as a motor fluid. A radial-flow turbine is shown; but 90 the novel features herein described and hereinafter to be claimed apply equally well to axial-flow turbines. The turbine-wheel A' is provided with a plurality of channels into which the downward extension R protrudes, 95 so as to form, with the turbine-wheels, buckets, as shown clearly in Fig. 5. By the steam-inlet E' the steam enters two nozzles H and H' somewhat contracted in cross-sectional area at their upper end, and the walls of which 100 diverge toward the inlet ends of the buckets. These nozzles are parallel with the channels and of a cross-sectional shape similar to that of the channels. They direct the steam into the inlet ends of the buckets, from the outlet 105 ends of which the steam enters the inlet end of a channel M of the casing, which channel is at every point throughout its length of the same cross-sectional area and serves to direct the steam after being subdivided, by means 110 of admission-blades F', into the inlet ends of the next series of buckets. The turbine-wheel is thereby propelled onwardly and the steam emanating from the outlet ends of these 115 buckets enters the inlet end of the next channel M' of the casing, which channel is also at every point throughout its length of the same cross-sectional area, but of larger size both in cross-sectional area and in height than the channel M. The channel M' directs the steam 120 again back to the inlet ends of the next series of buckets against which it impinges, and thereby propels the wheel onwardly and from which it emanates and enters either a suitable condenser or exhausts directly into the atmosphere. Those parts of the casing which 125

separate one channel from the other and which extend downwardly in proximity to the outlet ends of the buckets are scoop-shaped, as shown clearly in Fig. 3. No curved release-blades are shown; but, if it is specially desired, such may be used. It is seen that the steam passing from the steam-inlet successively through one series of buckets into and through a curved channel into the next series of buckets, through the same and into and through the next curved channel, and, finally, to the exhaust, partakes of a spiral path. The cross-sectional area of the channels increases relatively to the decrease in velocity of the steam. Complete acceleration takes place in the first set of nozzles, thus giving the motor fluid a high velocity, which is extracted step by step as it comes in contact with each separate series of buckets.

In Fig. 4 is shown another modified form of my improved turbine also adapted for the use of gas as a motor fluid and having the admission-blades and release-blades omitted. The inlet-nozzle H^2 , in communication with the steam-inlet E' of the turbine, is contracted in cross-sectional area at its upper end and its walls diverge, so as to direct the motor fluid into the first series of buckets. From the outlet ends of these buckets the motor fluid passes into the inlet end of the first channel N of equal cross-section throughout its length and guided by the same is directed into the inlet end of the next series of buckets, a drop in the velocity of the motor fluid having, due to the expending of part of the energy of the motor fluid in work of impulse and reaction, taken place. From the outlet ends of this series of buckets the motor fluid emanates and enters the next channel N' , also of equal cross-section throughout its length, but of larger size—that is, greater length and greater cross-section—than the channel N , through which the motor fluid first passed, this larger channel corresponding in cross-section to the different velocity of the motor fluid. The last-named channel guides the motor fluid into the next series of buckets through which it passes, propelling the turbine-wheel onwardly and from which it finally enters into a suitable condenser or exhausts directly into the atmosphere. The steam in passing from the steam-inlet to the steam-outlet of the casing successively through the series of buckets and channels partakes of a spiral path. The form of turbine shown in Fig. 4, of which a transverse section is not shown, has its casing provided with a downwardly-extending division-wall R' , similar to that hereinabove described and shown in Figs. 3 and 5. That part of the casing separating one channel from the other and in proximity to the outlet ends of the buckets is tapering in shape, but may also be made scoop-shaped, as shown in Fig. 3.

In some cases it is only necessary to use one spiral path, while in other cases it would be necessary to use two, depending in number on the drop or reduction in velocity of the motor fluid. One velocity reduction takes place when the motor fluid is admitted by the diverging nozzle, and a velocity reduction takes place for each separate channel. Hence in the turbine shown three velocity reductions take place. A turbine may be constructed having any number of velocity reductions, and also a turbine may be constructed in which the steam enters several steam-inlets at once, each separate stream partaking of a spiral path from the steam-inlet to the steam-outlet and each stream simultaneously passing through chambers successively greater in cross-section, depending on the drop in velocity, but each chamber of equal cross-section throughout its length.

Reference has been made to the casing as one belonging to the separate units shown in the drawings. A turbine having one or more steam-inlets, and consequently one or more units, as shown in the drawings, would be provided with a main casing surrounding both the units and turbine-wheel.

I do not wish to be understood that the channels must be exactly of the same cross-sectional area throughout, it being within the scope of my invention to use channels of "substantially" the same cross-sectional area throughout. In practice I have found it advisable to somewhat round off the corners of the channels of rectangular cross-section at the central part intermediately between the ends of the same, whereby in case of channels of smaller size the cross-section becomes somewhat elliptical.

Units of larger sizes are made by casting from metal with cored channels, rectangular at their inlet and outlet ends, with rounded-off corners at their central portion, the rectangular passages conforming with the arc of the bucket circle.

Units of smaller sizes may be constructed by bending tubes to form the spiral channel, forming the ends of these tubes into rectangular shape, with the central portion left somewhat elliptical.

In all cases where channels of rectangular cross-section are used the inlet and outlet ends of the spiral channels should be approximately rectangular in cross-section shaped to the arc of the bucket circle.

Having thus described my invention, I claim as new and desire to secure by Letters Patent—

1. A steam-turbine, comprising a casing, a turbine-wheel having a series of buckets with inlet and outlet ends, and means of substantially the same cross-sectional area throughout, adapted to guide the steam from the outlet ends of a number of buckets to the inlet

ends of buckets in proximity thereto and of the same series.

2. A steam-turbine, comprising a casing, a turbine-wheel having a series of buckets, and means of the same cross-sectional area throughout, adapted to guide the steam from the outlet ends of a number of buckets to the inlet ends of buckets in proximity thereto and of the same series, the means connecting each successive number of outlet and inlet ends being of larger size than the preceding means.

3. A steam-turbine, comprising a casing, having a series of channels each of the same cross-sectional area throughout its length, and a turbine-wheel having a series of buckets, with their ends in communication with the ends of the channels.

4. A steam-turbine, comprising a casing, having a series of channels of rectangular cross-section, each of the same cross-sectional area throughout its length, and a turbine-wheel having a series of buckets, with their ends in communication with the ends of the channels.

5. A steam-turbine, comprising a casing, having a series of channels each of different size, and each of the same cross-sectional area throughout its length, and a turbine-wheel having a series of buckets in communication with the ends of the channels.

6. A steam-turbine, comprising a casing, having a series of channels of rectangular cross-section, each of different size and each of the same cross-sectional area throughout its length, and a turbine-wheel having a series of buckets with their ends in communication with the ends of the channels.

7. A steam-turbine, comprising a casing, having a steam-inlet and a series of channels, each of the same cross-sectional area throughout its length, a nozzle in said casing in communication with the steam-inlet, parallel with said channels, and a turbine-wheel having a series of buckets with their ends in communication with the ends of the channels.

8. A steam-turbine, comprising a casing, having a steam-inlet and a series of channels, each of the same cross-sectional area throughout its length, a nozzle having divergent walls

50 in said casing, in communication with the steam-inlet and parallel with said channels, and a turbine-wheel having a series of buckets with ends in communication with the ends of the channels.

55 9. A steam-turbine, comprising a casing, having a steam-inlet and a series of channels, each of the same cross-sectional area throughout its length, a plurality of nozzles in said casing in communication with said steam-inlet, and a turbine-wheel having a series of buckets with ends in communication with the ends of the channels.

10. A steam-turbine, comprising a casing, having a plurality of channels each of different size, and each of the same cross-sectional area throughout its length, a plurality of admission-blades in said channels, and a turbine-wheel having buckets.

11. A steam-turbine, comprising a casing having a plurality of channels each of different size, and each of the same cross-sectional area throughout its length, a plurality of admission-blades, a plurality of curved release-blades, and a turbine-wheel having buckets.

12. A steam-turbine, comprising a casing having a plurality of channels each of the same cross-sectional area throughout its length, a turbine-wheel provided with curved channels, and a division-wall forming buckets with the channels of the turbine-wheel.

13. A steam-turbine, comprising a casing having a plurality of channels, each of the same cross-sectional area throughout its length, a turbine-wheel provided with curved channels, and a beveled division-wall forming buckets with the channels of the turbine-wheel.

14. A steam-turbine, comprising a casing having a plurality of channels, each of the same cross-sectional area throughout its length, a turbine-wheel provided with curved channels, and a stationary division-wall forming buckets with the channels of the turbine-wheel.

15. A steam-turbine, comprising a casing having a plurality of rectangular channels, each of different size and each of the same cross-sectional area throughout its length, a turbine-wheel having curved channels, and a division-wall forming buckets with the channels of the turbine-wheel.

16. A steam-turbine, comprising a casing having a steam-inlet and an exhaust, a plurality of channels each of different size and each of the same cross-sectional area throughout its length, and a turbine-wheel having buckets, said channels being adapted to guide the steam emanating from the outlet ends of one series of buckets, to the inlet ends of the next series, so as to cause the steam, passing successively through the channels and buckets to partake of a spiral path from the steam-inlet to the exhaust.

17. A steam-turbine, comprising a casing, having a steam-inlet and a series of channels, each of the same cross-sectional area throughout its length, a nozzle of cross-sectional shape similar to that of the channels in said casing, in communication with the steam-inlet, and a turbine-wheel having a series of buckets with their ends in communication with the ends of the channels.

18. A steam-turbine, comprising a casing, having a steam-inlet and a series of channels of rectangular cross-section, each of the same cross-sectional area throughout its length, a

nozzle rectangular in cross-section in said casing in communication with the steam-inlet, and a turbine-wheel having a series of buckets with their ends in communication with the ends of the channels.

5 19. A steam-turbine, comprising a plurality of units, one adjacent the other, each consisting of a casing having a steam-inlet and a series of channels, each of the same cross-sectional area throughout, and a turbine-wheel

with a series of buckets having their ends in communication with the ends of the channels.

In testimony that I claim the foregoing as my invention I have signed my name in presence of two subscribing witnesses.

JOHN W. SMITH.
